UNITED STATES PATENT OFFICE.

JOHN T. KELLY, OF NEW YORK, N. Y., ASSIGNOR OF ONE-HALF TO GEORGE M. JONES, OF PITTSBURG, PENNSYLVANIA.

DESIGN FOR A RADIATOR-VALVE BODY.

SPECIFICATION forming part of Design No. 33,257, dated September 25, 1900.

Application filed March 28, 1900. Serial No. 10,557. Term of patent 14 years.

To all whom it may concern:

Be it known that I, JOHN T. KELLY, a resident of New York, (Brooklyn,) in the county of Kings and State of New York, have invented and produced a new and original Design for a Radiator-Valve Body; and I do hereby declare the following to be a full, clear, and exact description thereof.

My design relates to a radiator-valve body, the essential features of which are the rounded form of the upper portion thereof, the curved and laterally-projecting lower portion, and intermediate the same an annular projection provided with angular faces.

In the accompanying drawings, illustrating my design, Figure 1 is a perspective view of the valve-body, and Fig. 2 is a side view of the same.

The upper portion of the valve-body is rounded, as at 1, and is provided with the threaded opening 2 in the top thereof and with the hollow laterally-projecting portion 3, provided with the projecting angular faces 4 and screw-threaded at its outer end. The

lower portion of the valve-body is curved, as at 5, and projects sidewise and is provided with the threaded opening 6, which is surrounded by the projecting angular faces 7. Intermediate the upper and lower portions of the valve-body is the annular projecting portion 8, provided with the angular faces 9. The rounded form of the upper portion of the body and the curved and laterally-projecting form of the lower portion thereof, together with the projecting angular faces intermediate said upper and lower portions, give to the valve-body a neat and compact appearance.

What I claim is—

The design for a radiator-valve body herein shown and described.

In testimony whereof I, the said JOHN T. KELLY, have hereunto set my hand.

JNO. T. KELLY.
